(57) **CLAIM**

The ornamental design for a combination shaving brush and razor blade holder, as shown and described.

DESCRIPTION

FIG. 1 is an orthographic view of a combination shaving brush and razor blade holder showing a first embodiment of my new design, the shaving brush and the razor blades are shown in broken lines for illustrative purposes only and form no part of the claimed design;

FIG. 2 is an orthographic view thereof;

FIG. 3 is a right side elevational view thereof,

FIG. 4 is a left side elevational view thereof,

FIG. 5 is a top plan view thereof,

FIG. 6 is a bottom plan view thereof;

FIG. 7 is a front elevational view thereof,

FIG. 8 is a rear elevational view thereof; and,

FIG. 9 is an orthographic view of a combination shaving brush and razor blade holder showing a second embodiment of my new design, wherein the shaving brush entry slot is not flared.
